AUTOMATIC LOCKING DEVICE

Walter J. Six, Indianapolis, Ind.

Application February 28, 1946, Serial No. 650,878

6 Claims. (Cl. 292—332)

1

This invention relates to an automatic locking device of a character that may be locked out of operation and manually conditioned for automatic locking of a closure under spring pressure upon the closure being moved to closed position.

One application of the invention, and as herein disclosed, has to do with the self-locking of a burial casket, there being provided a series of automatic locking devices along both the hinged and opening side, such as will automatically and permanently lock the lid in closed position for burial, and wherein the devices are contained and concealed within the casket.

One feature of the invention resides in the latching of the lock under tension in its unlocked position in a manner to cause it to become unlatched and automatically move into locking position through a camming action resulting from the movement of the closure to closed position.

Another feature of the invention resides in the provision of a manually movable withholding pin, such as to prevent the automatic locking of the device when in position, but removable for permitting of the locking action.

Another feature of the invention resides in the provision of a temporary locking pin, such as may be manually placeable and removable for temporarily locking the closure until such time as it is desired to have it automatically and permanently locked in closed position.

The full nature of the invention will be understood from the accompanying drawings and the following description and claims:

Fig. 1 is a perspective view of a burial casket indicating the relative location of a locking device thereon.

Fig. 2 is a vertical section through one of the locking devices.

Fig. 3 is a plan view showing the locking device in inoperative position with the closure swung open.

Fig. 4 is the same as Fig. 3, showing the locking device in its automatic locking position upon the closure being moved to closed position.

In the drawings there is illustrated a casket including an upright wall 10 forming the body portion thereof, and a hinged lid or closure 11. Said closure 11, as shown herein, includes a panel 12 and a sheet metal casing 13 hinged to the upright wall 10 by a hinge 14. The casing 13 is formed with a transverse locking plate 15 provided with a slot forming a keeper shown at 16.

Secured to the wall 10 of the interior surface hereof there are one or more tubular latching brackets 17 for housing a tension spring 18. Said

5 spring is anchored at its lower end to a pin 19 in the bracket and at its opposite end to the lower extreme end of a locking bolt 20. Said locking bolt is formed with a latching shoulder 21 on one side thereof for latching engagement with the upper end of the bracket 17, as shown in Fig. 3. In this position the locking bolt is latched out of locking position against the tension of the spring 18. Above the latching shoulder, intermediate the ends of the bolt, there is a pair of outwardly extending portions, such as to provide safety shoulders 22. Said safety shoulders are adapted to engage the top of the bracket 17 to limit the inward movement of the bolt therein under tension of the spring 18.

10 The upper head portion of the bolt is formed with an overhanging locking lip 23 extending laterally on one side thereof, and a camming surface 24 extending angularly along the upper portion of the opposite side thereof. Said bolt is supported by the bracket 17 under tension of the spring in position to extend through the slot in the locking plate for movement into locking engagement with the keeper at 16.

15 The upper portion of the wall 10 is flared outwardly at 25 to receive the hinge 14. Mounted longitudinally of the outwardly flared portion thereof there is a cross bar 26. Provision is made between the upper surfaces of the cross bar 26 and the locking plate of the closure for a sealing strip 27 such as to provide an air and water tight seal between the wall and the closure. The cross bar 26 is slotted at 28 to permit the bolt to pass therethrough and upwardly therefrom with a goose-neck formation, as illustrated in Fig. 2.

20 Adjacent the top of the cross bar opposite the bolt there is provision for slidably receiving a removable withholding pin 29 which may be inserted therein to extend through an aperture 30 in the cross bar 26. When said pin is in place, the bolt is withheld from operative action or movement into locking position. Similarly slidably through a looped plate 31 secured to the interior upper surface of the locking plate 15, there is a camming element in the form of a removable pin 32. The head or upper end of the bolt is apertured at 33 to receive the camming pin 32 when in place. Said camming pin serves a dual purpose of locking the closure through engagement with the bolt when the bolt is in its inoperative position shown in Fig. 3. In this position the pin is extending through the aperture 33 in said bolt. Also, in another operation said camming pin 32 operates to engage the camming surface 24 of the bolt in a manner to swing it free of its latched

inoperative position shown in Fig. 3, to its automatic locking position, as shown in Fig. 4.

In operation, when it is desired to readily remove or open the closure, the withholding pin 29 is in place to retain the bolt in its unlatched position, as shown in Figs. 2 and 3. When it is desired to temporarily lock the closure in its closed position, the camming pin 32 is inserted through the looped plate 31 and through the aperture 33 in the bolt, as shown in Fig. 2. When it is desired to automatically and permanently lock the closure in its closed position, the withholding pin 29 is removed, and with the lid in its open position free of the bolt, the camming pin 32 is inserted through looped plate 31. Since movement of the bolt is unguarded by the withholding pin 29 upon the closure being then moved to closed position, the camming pin 32 is pressed against the camming surface 24 of the bolt, such as to cam it to one side and thereby cause it to become unlatched. The latching shoulder 21 being thus moved free from engagement with the upper end of the housing 17, the spring 18 will snap the bolt downwardly in a manner to throw the locking lip 23 laterally into locking engagement with the keeper 16 of the latching plate 15. Thereupon the closure will be automatically and permanently locked in closed position without access to the bolt for opening it.

The invention claimed is:

1. An automatic locking device comprising a latching bracket, a locking bolt slidable longitudinally thereof relative to said bracket, a latching shoulder on said bolt engageable with said bracket to retain said bolt in inoperative position, a spring operatively connecting one end of said bolt with said bracket tending to draw said bolt into locking position under spring tension restrained by said latching shoulder when engaged with said bracket, a locking plate on the closure to be locked, a head on the other end of said bolt having a locking lip and camming surface, and means provided on said locking plate engageable with the camming surface of said bolt for camming said bolt out of its latching engagement with said bracket into position for its locking lip to engage said locking plate to thereby lock said closure under tension of said spring.

2. An automatic locking device for a structure having a closure therefor, said closure having a slotted locking plate, a bracket mounted on said structure, a locking bolt having adjacent one end thereof a latching shoulder engageable with said bracket, a tension spring connecting said end of the bolt with said bracket for retaining said bolt in its inoperative latched position thereon, said bolt having a head portion at the opposite end thereof formed with a locking lip and camming surface to extend through a slot in said plate, and means on said plate for engaging the camming shoulder of said bolt upon said closure being moved to closed position for camming said bolt free of latching engagement with said bracket and into position for its locking lip to engage and lock said plate under tension of said spring.

3. An automatic locking device for a structure having a closure therefor, said closure having a slotted locking plate, a bracket mounted on said structure, a locking bolt having adjacent one end thereof a latching shoulder engageable with said bracket, a tension spring connecting said end of the bolt with said bracket for retaining said bolt in its inoperative latched position thereon, said bolt having a head portion at the opposite end thereof formed with a locking lip and camming

surface to extend through a slot in said plate, and a removable camming pin carried by said plate movable thereon into position for engagement with said camming surface to cam said bolt laterally from inoperative position to locking position with said plate, said movement releasing the latching shoulder from said bracket and causing said locking lip to engage and lock with said plate under tension of said spring.

4. An automatic locking device for a structure having a closure therefor, said closure having a slotted locking plate, a bracket mounted on said structure, a locking bolt having adjacent one end thereof a latching shoulder engageable with said bracket, a tension spring connecting said end of the bolt with said bracket for retaining said bolt in its inoperative latched position thereon, said bolt having a head portion at the opposite end thereof formed with a locking lip and camming surface to extend through a slot in said plate, means on said plate for engaging the camming surface of said bolt upon said closure being moved to closed position for camming said bolt free of latching engagement with said bracket and into position for its locking lip to engage and lock with said plate under tension of said spring, and a removable withholding pin in said structure for retaining said bolt in shoulder latching position against camming movement upon said closure being moved to closed position.

5. An automatic locking device for a structure having a closure therefor, said closure having a locking plate thereon, a bracket on said structure, a locking bolt movably associated with said bracket, a spring connected with one end of said bolt, a locking head at the other end of said bolt having a locking lip on one side thereof and a camming surface on the opposite side, a latching shoulder on said bolt intermediate the ends thereof for engagement with said bracket to hold said bolt out of locking position against the tension of said spring, the head of said bolt being provided with an aperture therein, and a camming pin removably carried by said plate to extend through said aperture for releasably locking said closure in closed position, said pin being removable from the aperture of said bolt and replaceable on said plate when said closure is in open position for engagement with the camming surface of said bolt upon said closure being moved to closed position for moving said bolt relative to said bracket and plate to release its latching shoulder from said bracket and cause its locking lip to lock with said plate under tension of said spring.

6. An automatic locking device for a structure having a closure therefor, said closure having a plate thereon, a bracket on said structure, a locking bolt movably associated with said bracket, a spring connected with one end of said bolt, a locking head at the other end of said bolt having a locking lip on one side thereof and a camming surface on the opposite side, a latching shoulder on said bolt intermediate the ends thereof for engagement with said bracket to hold said bolt out of locking position against the tension of said spring, the head of said bolt being provided with an aperture therein, and a camming pin removably carried by said plate to extend through said aperture for releasably locking said closure in closed position, said pin being removable from the aperture of said bolt and replaceable on said plate when said closure is in open position for engagement with the camming surface of said bolt upon said closure being moved to closed

position to thereby release its latching shoulder from said bracket and cause its locking lip to lock with said plate under tension of said spring.
